UNITED STATES PATENT OFFICE.

WALTER E. SNODGRASS, OF HULL, ILLINOIS.

WAGON-STANDARD.

No. 805,034.

Specification of Letters Patent.

Patented Nov. 21, 1905.

Application filed October 26, 1904. Serial No. 230,043.

To all whom it may concern:

Be it known that I, WALTER E. SNODGRASS, a citizen of the United States, residing at Hull, in the county of Pike and State of Illinois, have 5 invented a new and useful Wagon-Standard, of which the following is a specification.

The invention relates to improvements in wagon-standards.

The object of the present invention is to improve the construction of wagon-standards and to provide a simple, inexpensive, and efficient device of great strength and durability adapted, in the event of wagon-beds, racks, loads of lumber, wood, &c., being loose, to enable the same to be tightly clamped and securely held on the running-gear.

A further object of the invention is to provide a device of this character which is capable of convenient operation to engage and 20 release a load and which will be entirely out of the way when not in use.

With these and other objects in view the invention consists in the construction and novel combination and arrangement of parts hereininafter fully described, illustrated in the accompanying drawings, and pointed out in the claims hereto appended, it being understood that various changes in the form, proportion, size, and minor details of construction within 25 the scope of the claims may be resorted to without departing from the spirit or sacrificing any of the advantages of the invention.

In the drawings, Figure 1 is an elevation of a bolster and a pair of standards provided 35 with clamping devices constructed in accordance with this invention. Fig. 2 is a vertical sectional view of one of the standards and the clamping device thereof. Fig. 3 is a horizontal sectional view on the line 3 3 of Fig. 2. 40 Like numerals of reference designate corresponding parts in all the figures of the drawings.

1 1 designate standards arranged at the ends of a bolster 2 in the ordinary manner and designed to be constructed of wood and provided with a metal strip or band 3 of the usual construction; but the standards may be constructed in any desired manner, as will be readily understood. At the inner faces of the 45 standards are arranged vertically-disposed clamping members consisting of plates or bars 4, which are connected with the standards by adjusting-screws 5, whereby they are adapted to be moved inward and outward to

clamp and release a wagon-bed, rack, or a 55 load.

The adjusting-screws, which may be of any desired number, are preferably arranged at the upper and lower portions of the standards, and they engage threaded perforations of the metal strap or strip 3; but the screw-threads of the standards may be provided in any other desired manner. The outer ends of the adjusting-screws are provided with heads 6, which may be of polygonal form to receive a 60 wrench, or any other desired form. The inner ends 7 of the screws are reduced and pass through perforations 8 of the upright clamping members, and after the parts are assembled the reduced ends 7 are headed, as shown 65 at 9, to retain the clamping bars or members on the inner ends of the screws. By this construction the inner ends of the screws are swiveled to the clamping-plates and are adapted to rotate on the same.

The clamping bars or members are adapted to lie flat against the inner faces of the vertical standards when the clamping devices are not in use; but when the wagon body or bed is removed and a loose load placed on the running-gear the said load may be firmly clamped and securely held in place. Also in the event of a loose wagon bed or body or hay or stock rack the same may be firmly clamped on the running-gear. The clamping bars or members are engaged by the shoulders formed by reducing the inner ends of the screws, so that the reduced outer ends are not subjected to the strain incident to the clamping action of the bars or members.

It will be seen that the device is exceedingly simple and inexpensive in construction, that it is adapted to be readily applied to the ordinary vehicle-standards, and that it is capable of firmly clamping a wagon-box, rack, or load 95 on the running-gear and of readily releasing the same. It will also be seen that the adjusting means, which force the clamping-plates inwardly, serve as the means for supporting the same.

Having thus fully described my invention, what I claim as new, and desire to secure by Letters Patent, is—

1. The combination of a standard having threaded apertures, adjusting-screws mounted in the threaded apertures of the standard, and a clamping member carried by the clamping-screws in their inward and outward movement

and being positively forced inwardly by the said screws to clamp a body, rack or load.

2. The combination of a standard having threaded openings, a vertical clamping-plate 5 arranged at the inner face of the standard, and clamping-screws mounted in the threaded openings of the standard and extending entirely through the same and having their inner ends swiveled to the clamping-plate, 10 whereby the latter is supported in position

for engaging a body, rack or load, said clamping-screws being adapted to positively force the clamping-plate inwardly.

In testimony that I claim the foregoing as my own I have hereto affixed my signature in the presence of two witnesses.

WALTER E. SNODGRASS.
